UNITED STATES PATENT OFFICE.

HARRY MORTIMER SPECHT, OF PELHAM, NEW YORK.

VARIABLE CONDENSER.

Application filed June 5, 1924. Serial No. 717,969.

This invention relates to a variable condenser and the novelty consists in the adaptation and arrangement of parts as will be more fully hereinafter pointed out.

5 This is an improvement of my variable condenser described in and claimed in my application Serial No. 681,483, filed December 19, 1923, and embodies the same advantage disclosed in that application of a condenser constructed in such a manner as to prevent the possibility of contact of the interleaving plates and substantially increasing the amount of plate space for holding the electrons and protons, accomplishing 15 this in a reduced space thereby increasing the efficiency in the handling of E. M. F. as compared to the condensers of the prior art.

20 My device is also adapted to accomplish the result of two condensers in one both in volume of E. M. F. and in the variation of the possible adjustments in regard thereto. In this way my device obviates the necessity of a vernier attachment as the division of 25 the rotor members into quarter spherical concentric plates permits of very fine adjustments, each rotor being independently operated and adjusted.

20 Referring to the drawings Figure 1 is an 30 illustrative cross vertical section showing the shafts and one of each of the cup members of the rotor and stator series in the interleaved position. Figure 2 is a longitudinal vertical section of my device on the line 35 2-2 of Figure 1. Figure 3 is a cross section on the line 3-3 of Figure 4. Figure 4 is a perspective of the middle slotted shaft. Figure 5 is a perspective of the outer slotted shaft broken away for convenience in illustration. Figure 6 is a vertical section on the line 6-6 of Figure 5. Figure 7 is a detail of the electrical connections shown at the left hand end of Figure 2.

40 In the drawings 10 is a central shaft to 45 which is rigidly secured concentrically a series of quarter spherical cup members 11 and said shaft 10 has the usual rotor handle 12 also rigidly secured thereto. A cylindrical insulating member 13 is adapted to slide 50 over said shaft 10 and an intermediate hollow cylindrical shaft 14 is adapted to be mounted over said shaft 10 and the insulating member 13 and to said shaft 14 is rigidly secured concentrically a second series 55 of quarter spherical cup members 15 and a rotor handle 16 is rigidly secured to the

outer end of said shaft 14. The shaft 14 has slots 17 permitting the quarter spherical cup members 11 to pass therethrough and rotate as may be desired. An insulating 60 member 18 is mounted over said hollow cylindrical shaft 14 and an outer hollow cylindrical shaft 19 is mounted over said insulating member 18 and the shaft 14. A series of concentric quarter spherical cup 65 members 20 is rigidly mounted on one side of said shaft 19 and a second series of concentric quarter spherical cup members 21 is rigidly mounted on the opposite side of said shaft 19 in a position diametrically opposed 70 to the first series of cup members 20. The shaft 19 is slotted at 22 and 23 to provide for the passage through and the movements of the two series of quarter spherical cup members 11 and 15 and said shaft 19 is a 75 fixed shaft which is not adapted to move but is a stator shaft.

In assembling my device central shaft 10 will have cylindrical insulating member 13 mounted thereover. Intermediate hollow 80 cylindrical shaft 14 will then be mounted thereover and cylindrical insulating member 18 will be mounted thereover. Outer hollow stator cylindrical shaft 19 will then be mounted thereover. The shaft 10, insulating 85 member 13, hollow cylindrical shaft 14, insulating member 18 and outer cylindrical shaft 19 will in this way be assembled in their proper positions before the quarter spherical cup members are mounted. Shaft 90 14 has slots 17 and shaft 19 has slots 22 and 23, all of which permit the described movement of the quarter spherical cup members 11 and 15 and said spherical cup members 11 and 15 will be rigidly secured to said 95 shafts 10 and 14 respectively in the usual and well known manner through slots 17 of shaft 14 and slots 22 and 23 of shaft 19, the insulating members 13 and 18 having the necessary slots in alignment with the afore- 100 mentioned slots as shown in the drawing. The quarter spherical cup members 20 and 21 will then be rigidly mounted in the usual well known manner to the shaft 19 in the 105 positions as described and shown in the drawing.

On the end of the shaft 19 opposite to the rotor handles 12 and 16 is adapted to be mounted by means of a nut 24 insulated by the outer annular insulation member 25 110 and by means of a nut 26 insulated by means of the inner annular insulation member 25

and also by annular insulation member 27, electrical terminal connections of usual construction 22^a which connects with the stator cup members 20, and 23^a which connects with the rotor cup members 11 and 15.

The operation of my device is most simple and the series of rotor cup members 15 may be turned into the full interleaved position with the stator cup members 20 as shown 10 in Figure 1 by means of turning the handle 16 so that they are in the position shown in Figure 1 and the rotor cup members 11 may be turned in a similar manner into full interleaved position with the stator cup members 21 as also shown in Figure 1 by the turning of the handle 12. Either of the 15 series of cup members 15 or 11 may be left in the open or non-interleaved position as shown in dotted outline in connection with 20 the rotor cup members 15 in Figure 1 and the other series of rotor cup members turned until the position desired is found or if it is desired the two handles 12 and 16 may be turned together so that the rotor cup members 25 11 and 15 may be turned simultaneously. It is thus seen that many variations may be effected by means of my device as the two series of rotor cup members 11 and 15 may be operated together or separately and 30 when one series has been adjusted the other may be very slightly turned in order to effect the result usually obtained by means of a vernier.

Many other means than those shown may 35 be used for carrying out the invention described and claimed without departing from the spirit of said invention as the device shown illustrates merely one way of carrying out my invention.

40 My device is adapted to effect a low loss, that is the construction is such as to reduce the leakage of electric radio current in a very substantial manner as compared with the prior art devices, thereby increasing the 45 efficiency of the condenser. It is also apparent that the construction of my device is such as to make it more dust proof and moisture proof than the flat plate type of condenser of the prior art and the encasing 50 of my device in a glass outer container would make it absolutely dust and moisture proof. Through the usual operation of my device greater selectivity is possible, more distance and a remarkable increase in vol-

ume, all of which are most essential features 55 in the operation of a radio receiving set.

I claim:

1. A variable condenser comprising two series of concentric stator quarter spherical cup members mounted diametrically opposite to each other and two series of concentric rotor quarter spherical cup members also mounted diametrically opposite to each other and lying between said two stator series in the open position and means for rotating 60 both series of said rotor members.

2. In a variable condenser the combination of a series of concentric rotor quarter spherical cup members rigidly secured to a central shaft, two series of concentric stator quarter spherical cup members rigidly secured diametrically opposite each other to a suitably slotted shaft mounted over said central shaft and insulated therefrom, a second series of concentric rotor quarter 70 spherical cup members rigidly secured to a second slotted shaft mounted over said first slotted shaft and insulated therefrom, together with connecting terminals on each of 75 said shafts.

3. A variable condenser comprising two series of concentric stator quarter spherical cup members secured in a position diametrically opposite each other, two series of concentric rotor quarter spherical cup members 80 85 mounted between said two stator series each adapted to turn into and out of full interleaved relation between one of the series of stator cup members and means for effecting such interleaved relation independently controlled for each series of rotor cup members.

4. In a variable condenser the combination of two series of concentric stator quarter spherical cup members secured in a position diametrically opposite each other, two series 90 of concentric rotor quarter spherical cup members each series independently controlled and each adapted to engage in interleaved relation one of the said stator series simultaneously.

5. In a variable condenser two series of concentric stator quarter spherical cup members, two series of concentric rotor quarter spherical cup members and means for operating the two rotor series independently. 105

In testimony whereof I affix my signature.

HARRY MORTIMER SPECHT.
